OLSON & BEAR LLP(57) **CLAIM**

The ornamental design for a ship as shown and described.

DESCRIPTION

FIG. 1 is a front, perspective view of a ship, according to our new design;

FIG. 2 is a left, plan view thereof;

FIG. 3 is a right, plan view thereof;

FIG. 4 is a top, plan view thereof;

FIG. 5 is a fore, plan view thereof;

FIG. 6 is an aft, plan view thereof;

FIG. 7 is a back, perspective view thereof;

FIG. 8 is a right, perspective view thereof; and,

FIG. 9 is a left, perspective view thereof.

The broken lines illustrate portions of the ship that form no part of the claimed design.
